UNITED STATES PATENT OFFICE.

EMORY E. TROWBRIDGE, OF KANSAS CITY, KANSAS.

AIR-VENT DRAINAGE SYSTEM.

1,408,548.

Specification of Letters Patent. Patented Mar. 7, 1922.

Application filed April 5, 1920. Serial No. 371,271.

To all whom it may concern:

Be it known that I, EMORY E. TROWBRIDGE, a citizen of the United States, residing in Kansas City, county of Wyandotte, and State of Kansas, have invented certain new and useful Improvements in Air-Vent Drainage Systems, of which the following is a specification.

My invention relates to improvements in an air vent drainage system and refers more particularly to a drainage system for venting and draining the soil and subsoil to maintain the same, at all times, in a substantially dry condition.

Among its salient objects are to provide a system for removing the surplus water from the ground and at the same time, ventilating or aerating the soil, thus maintaining a more uniform character to the soil, regardless of weather conditions; to provide a system which is particularly adapted to the draining of moist or swampy farm lands, and one that is especially applicable to the proper maintenance of road beds, pavements, public highways, rail roads and other transportation lines; to provide a system for maintaining the soil and subsoil in a substantially uniform condition regarding moisture and air beneath the surface of the ground.

In the single figure is shown a sectional view of a section of soil and subsoil with the system viewed diagrammatically therein, the pipe line shortened up by breaking parts away.

It is a matter of general information among tile manufacturers that drain tile installed in earth that is water-logged or soggy will delay, for a considerable time, the carrying off of the moisture. It will drain the water only after the soil has been aerated by the atmosphere that would slowly permeate through the soil or seep out through the joints of the pipe. In the present system, I provide means for introducing air into the soil, thus hastening the drainage and preventing waterlogging of the communicating lines.

The gravity weight of the atmosphere at sea level is about 14.7 pounds per square inch, which will cause the air to enter every possible opening it can reach. The air vent system provides surface openings and ducts for permitting the atmosphere to enter the

soil from below, to aid in removing the surplus moisture, eliminate abnormal conditions and prevent either the accumulation of excess moisture, or the drying out and opening of crevices in the subsoil, also the abnormal conditions caused by freezing and thawing where any quantity of moisture is present.

In Fig. 1 is shown only a portion of the drainage system, the horizontal drains being broken away in order to show more comprehensively a greater part of the system. It is understood that there may be a network of horizontal drain lines where a large tract of land is to be drained and at different parts of the system vertical surface ducts may be connected to the horizontally positioned drain line. Such a system will greatly facilitate the drainage of water or the supplying of moisture and air to the soil and sub-soil.

Referring to the drawings, at 1 is shown a section of earth or subsoil in cross section. Vertical surface vents 2 extending down through the subsoil connect with horizontal ducts 3, which comprise the connecting links and drain lines of the system. At the top of these surface vents are mounted an open ended T-tile 2^a, which permits the atmosphere to circulate freely down through the system. Connected to the vertical surface vents are horizontally extending ducts 4 and 5, duct 4 having an open ended T-connection 6, vertically positioned connected thereto, and duct 5 a similar T-connection 7 horizontally positioned, connected thereto, both being arranged in the subsoil and adapted to collect the moisture therefrom and supply surface air thereto. Extending vertically from the horizontal duct 3 is a duct 8, which has a similar open ended T-connection 9, similarly adapted to collect the moisture and supply air to the subsoil, the only difference being that it is connected directly to the horizontally extending lower drain. About the open ends of these T-connections, which draw or supply moisture to the soil and aerate the same, I put a quantity of comminuted material 10, such as coarse gravel, or crushed stone, which will facilitate the passage of moisture from the subsoil to the respective open ended connections and at the same time, facilitate the circulation of air from the ducts to the soil.

In the single figure, I have shown only a

small part of a drainage system and have shown only a few of the possible open ended connections beneath the subsoil. Where it is desired to drain the subsoil deeper, it may be more advantageous to supply two or three open ended connections on either side of the vertical surface vents and arrange them at frequent intervals along the lower horizontal ducts. The character of the soil and 10 the quantity of moisture to be drained will, of course, determine to a great extent, the positioning of the subsoil drawoffs.

About the open ended T-connections 2^a mounted at the surface of the ducts 2, ventilating boxes such as that shown at 11 may be placed to prevent the breaking off of these connections or damaging them for any reason. These boxes may be of any material such as concrete or wood as desired, and ventilating holes 12 arranged therein to permit free circulation of the atmosphere. Horizontal ducts such as that shown at 3 will, of course be laid in different directions through the soil to be drained and graded 20 to carry off the moisture, to drain ducts such as that shown at 13. The tile used for the respective ducts and drains may be of any suitable type such as that commonly used, but preferably in this system I employ a 30 vitrified earth tile with a special type of connection which will be the subject of a subsequent application.

Where the soil is of heavy loam or of clayey character, the coarse material or 35 crushed stone about the subsoil drawoffs is more essential than where the soil to be drained is of a coarse or loose character. The circulation of the air from the surface through the subsoil will be assisted by the 40 difference in temperature of the atmosphere and the temperature of the subsoil. Also, it may be desirable to supply moisture to the subsoil instead of draining it therefrom and in this case, water may be supplied to 45 the vertical surface ducts to the mount desired.

Where an air vent drainage is used in connection with farm lands, the aerating of the subsoil makes the land more productive due to the maintaining of more constant conditions of moisture and temperature. When pavements have been laid that are waterproof and the natural ventilation and surface moisture either shut off or trapped 50 thereunder, an abnormal condition is created, by which there may be an accumulation of surplus moisture from capillary attraction, and at other times, there may be an excessive 55 drying out causing the subsoil to crack with 60 a consequent splitting and disintegrating of the pavement.

By keeping the subsoil properly drained and aerated these abnormal conditions are obviated. In the case of public highways 65 where the surface is not waterproofed all

road engineers agree that proper drainage is absolutely essential. This is also true in the case of railroads and other transportation lines and a healthy, resilient road bed can be maintained by this drainage system. 70 Under numerous other conditions will the effective draining and aerating of the soil be a decided advantage, both to the yielding qualities of the soil and to the physical characteristics or changes due to the more constant conditions of moisture, temperature and air maintained therein.

I claim as my invention:

1. A drainage system of the character described, comprising a plurality of connected 80 ducts laid in a substantially horizontal position beneath the surface of the ground, surface vents connected therewith, open ended vertically and horizontally extending secondary drain ducts connected to the system and adapted to draw off the moisture from the body of the subsoil and supply air thereto, drain ducts for carrying off the moisture of the soil connected to the system.

2. A drainage system of the character described, comprising a plurality of connected ducts laid in a substantially horizontal position beneath the surface of the ground, surface air vents connected therewith, open ended vertically and horizontally extending 95 secondary drain ducts below the surface of the ground connected to the system and adapted to draw the moisture from the subsoil and supply air thereto, means for facilitating the passage of the moisture and air 100 from the open ended underground ducts to the body of the subsoil, drain ducts connected to the system for carrying off the moisture.

3. A drainage system of the character described, comprising a plurality of connected ducts laid in a substantially horizontal position beneath the surface of the ground, surface vents connected therewith, open ended vertically and horizontally extending secondary 110 ducts below the surface of the ground connected to the main ducts adapted to draw off or supply moisture to the body of the subsoil and at the same time supply air thereto, drain ducts connected to the system for carrying off the moisture therefrom.

4. A drainage system of the character described, comprising a plurality of connected horizontal ducts laid in substantially horizontal position beneath the surface of the ground, vertical surface vent ducts connected with the horizontally positioned drain ducts, open-ended vertically extending secondary 125 ducts below the surface connected with the horizontal drains and adapted to draw off or supply moisture to the sub-soil and open horizontally extending secondary ducts below the surface connected to the vertical surface vents, said open-ended secondary sub-surface ducts adapted to draw off or 130

supply moisture to the sub-soil and supply air thereto, and a drain outlet for relieving the system of moisture.

5. A drainage system of the character described, comprising a plurality of connected ducts laid in a substantially horizontal position beneath the surface of the ground, sur-

face vents connected therewith, open ended secondary drain ducts connected to the system and adapted to draw off the moisture 10 from the body of the subsoil and supply air thereto and drain ducts for carrying off the moisture of the soil connected to the system.

EMORY E. TROWBRIDGE.
